UNITED STATES PATENT OFFICE.

HENRY MAAS, OF HOMESTEAD, IOWA.

IMPROVEMENT IN ROTARY PUMPS.

Specification forming part of Letters Patent No. 55,318, dated June 5, 1866.

To all whom it may concern:

Be it known that I, HENRY MAAS, of Homestead, Iowa county, State of Iowa, have invented new and useful Improvements in Rotary Pumps; and I do hereby declare that the following is a full, clear, and exact description thereof, which will enable others skilled in the art to make and use the same, reference being had to the accompanying drawings, forming part of this specification, in which—

Figure 1 is a side elevation of the pump-casing; Fig. 2, a plan or top view of the lower section of the pump-casing, with the upper section and revolving disk or plate-ring of the same removed; Fig. 3, a central vertical section taken in the plane of the line $x x$, Fig. 2, with all the working parts of the pump and the two sections of its casing placed properly together and fastened; Fig. 4, a view of the under side of the revolving disk or plate-ring, and Fig. 5 a plan view of the interior of the upper casing with all the operating parts removed.

Similar letters of reference indicate like parts.

A in the drawings represents a hollow round casing divided into two equal parts or sections, B B, secured together by screws or in any other proper manner.

C is a ring placed between the two sections of the pump-casing, resting upon a shoulder, D, of the lower section and turning in a corresponding annular-shaped groove, E, of the upper section.

F represents a series of four flat arms extending from the inner edge, G, of the ring C to the center concentric hub, H. These arms are wider at their outer ends than at their inner, and are at equal distances apart, with an opening, I, between every two of them, which openings are all similar in shape and each bounded by that portion of the inner side of the ring C and the periphery of hub H included between the edges of every two of the arms F. Each of the arms F, both upon their upper and lower sides, have a shoulder, J, extending in the direction of their length, and in a radial line with the center of the ring C. The hub H projects above the upper edge of the ring C, but is in the same line with its lower edge. Each of the openings I of the ring C, formed as above explained, is closed by a plate, J, cor-

responding in shape thereto, resting upon the shoulder portion of the upper side of one of the arms F and fitting the shoulder of the under side of the next arm thereto, either toward the right or left, as the case may be, which plates are of the same thickness as the arms, and are each hung so as to balance, by trunnion-pins, a, one upon their outer circular-shaped edge, fitting the inner side of the ring C, and the other upon their edge fitting the periphery of the hub, but in a radial line with each other from the common center of the hub and ring, turning respectively in suitable bearings of the ring and its hub at the proper points therefor. The inner trunnion-pin of each plate, J, has a similar quadrant-shaped arm, K, which arms, when the plates are horizontal or resting upon the shoulder portions of the upper side of the ring-arms F, project downward in a plane at right angles thereto, their curved edges corresponding in shape to the stationary annular cup-shaped cavity L of the central portion of the lower casing-section.

M is a vertical shaft passing loosely through the upper section of the casing A and the center of the ring-hub H, with diametrical notches c of which it is interlocked by its diametrical pins d, turning at its lower end in a suitable-shaped socket or bearing, N, in the lower section of the casing A. By turning this shaft either to the right or left it necessarily turns with it the ring and hub, with the series of plates balanced between them, as explained, each of which, as the quadrant-shaped arms of their inner trunnion-pins, upon which they are hung, abuts in turn against the stop O, formed in the annular cup-shaped cavity K of the lower casing-section, are swung upward from their seat upon the ring and hub arms and brought into a vertical position, or a plane at right angles thereto, the quadrant trunnion-arms of such plates then lying in the annular-shaped recess P, surrounding the shaft M, in the under side of the hub, from which position, by continuing the rotation of said shaft, they (the said plates) are swung down again into a horizontal position upon or in the same line with their ring-arms, from which they were raised or swung up, as explained, by their abutment, in turn, against the corner Q and inclined edge R of the block or stop S at one portion of the annular-shaped channel or way T of the upper

casing-section, the transverse section of which, in connection with the annular channel or way U of the lower section, corresponds exactly to the periphery or edge of the ring-plates or wings as they move around in the same. In this horizontal or flat position they remain as they in turn pass between the lower face of the said block of the upper casing-section and a block, T, in a position and of a length corresponding thereto, or nearly so, of the lower section, the space between these two blocks being equal to the entire thickness of the plates when the quadrant-arms of the plate trunnion-pins in turn again abutting against the stop of the cup-shaped cavity of the lower section, the plates are again in turn swung up into a vertical position, and again moved back into a horizontal position as they strike the corner Q and inclined edge R of the upper section of the casing-block S, when, as each, in turn, passing between such blocks S and the block corresponding thereto in the lower section, it is again swung in a vertical or right-angular position with regard to the rotating ring, as before explained, and so on as long as the shaft is turned.

From the above description of the manner in which the several plates hung to the revolving ring or disk C of the pump-casing are operated in connection with the internal construction of the latter and the general arrangement of the whole together, it is plain to be seen that if the pump be placed in the bottom of the well, for instance, with a suitable open-

ing made in its casing to allow water to enter it at such part or portion of the same as the plates are swung into a vertical position, or, in other words, at right angles to the plane of rotation of the common ring in which they are hung, as described, the water thus admitted will be carried around with the plates and by them discharged from the pump-casing through a suitable outlet or escape therefor leading up through the well, arranged at such point of the pump-casing as the plates are swung back into line, or so as to coincide with the plane of rotation of their common ring, thereby causing the water to be forced up from and out of the well, as is obvious without any further explanation, it being here advisable, however, to state, in conclusion, that it is necessary that all the working and sliding parts of the pump should be water-tight so far as possible and practicable.

I claim as new and desire to secure by Letters Patent—

The disk or ring C, having a series of plates, J, hung in and to the same, when arranged within a casing having an outlet and inlet opening thereto in such a manner that it can be rotated, and the said casing is so constructed as to operate the said ring-plates J substantially in the manner and to accomplish the purpose described.

HENRY MAAS.
